UNITED STATES PATENT OFFICE.

AXEL S. VOGT, OF PHILADELPHIA, PENNSYLVANIA.

WATER-TUBE BOILER.

SPECIFICATION forming part of Letters Patent No. 634,045, dated October 3, 1899.

Application filed February 7, 1899. Serial No. 704,795. (No model.)

To all whom it may concern:

Be it known that I, AXEL S. VOGT, a resident of Philadelphia, in the county of Philadelphia and State of Pennsylvania, have invented certain new and useful Improvements in Water-Tube Boilers, of which the following is a specification.

These improvements in water-tube boilers provide for the ready withdrawal of any nest of tubes without disturbing the others, permit the ready adjustment of the baffles, secure facility for expansion, provide for uninterrupted steaming, and secure generally a high degree of convenience, economy, and efficiency.

In the accompanying drawings, Figure 1 is a front elevation of a water-tube boiler embodying these improvements. Fig. 2 is a front view, in vertical section, parallel to the view shown in Fig. 1. Fig. 3 is a side view, in vertical section, at right angles to the view shown in Fig. 1. Fig. 4 is a partial rear elevation. Fig. 5 is a sectional elevation illustrating the connections between the rear water-legs and risers. Fig. 6 is a sectional elevation illustrating the connections between the front risers and the drum.

Referring to the drawings, the foundations 1 and 1' support the front water-legs 2 and 2' and the rear water-legs 3 and 3'. The water-legs 3 and 3' are connected together by the water-boxes 4 and are connected directly to the drum 5, the water feeding from the drum downward through the legs into the boxes. The water-legs 2 and 3 are connected by the water-boxes 6 and the water-tubes 7, forming, with the insulating material 8, end walls for the construction. The water-legs 2' and 3' are connected by the water-boxes 6' and by the double row of tubes 7', between which is placed a wall 8' of insulating material, such as slabs of asbestos, magnesia, or other refractory material. A grate 9 is provided in each of the combustion-chambers, limited by the walls 8 and 8', the construction forming two practically independent combustion-chambers, each of which may be operated independently of the other. The rear risers 10 rest loosely upon the chairs 11, supported upon the water-boxes 4. The front risers 12 rest loosely directly upon the girders 13, per-

forated; as at 13', to permit air to pass into the combustion-chambers and alternately upon the chairs 14, supported by the girders 13. The short risers provide hand-holes 15, which afford access for cleaning and through which the baffle-plates 16 may be adjusted, these plates resting upon the lower tubes 17 of the long risers. The hand-holes are closed with insulating-covers. The baffles 16 and 16' are rendered accessible from the ends of the construction by forming the end walls 8 with removable sections 8" opposite the baffles. The front and rear risers are connected together, respectively, by the tubes 17. The front risers and water-legs are connected to the drum by the tubes 18.

Each of the rear risers 10 is connected to the water-box 4 by a valved bend. The bend comprises a nipple 20, screwed into the riser 10, upset as at 21, locked by a nut 22, and having a flange 23, a nipple 24, screwed into the water-box 4, upset as at 25, locked by a nut 26, and having a flange 27, a joint 28, having flanges 29 and 30 for attachment to the respective flanges 23 and 27, a cap 31 for permitting access to the interiors, and a valve 32, which seats upon the port 33 and closes the communication between the water-box 4 and the riser 10.

Each of the front risers 12 has a sleeve connection with the corresponding tube 18 where it is held by the nuts 34 and 35. Where joints of this character are employed, they may be made water-tight by the use of soft-metal rings or packings, as 34' and 35'. The section of the tube which lies within the riser is provided with ports 36, through which water passes from the riser into the tube. The interior of the tube is tapered inwardly from a point near the end to a point beyond the ports, as at 40, to provide for the action of the conical valve 37, which may be moved longitudinally to the point 40 to close the tube. This valve is swiveled on the threaded valve-stem 38, which may be moved through a plug 39, screwed into the end of the tube. A stuffing-box 39', fixed in the plug 39, and a cap 41, screwed on the end of the tube, afford a suitable closure for the tube end. When the front risers are to be withdrawn, the valve 37 is run in to the point 40, closing the tube.

The cap 41 and the nuts 34 are then removed, when the riser may be disconnected.

As each rear riser 10 and its corresponding front riser 12 with their connecting-tubes 17 have no steam and water connections with the system and no fixed connections but the bend connection with the water-box 4 and the sleeve connection with the tube 18, it will be seen that by closing the valves 32 and 37, disconnecting the flanges 23 and 29, and removing the cap 41 and the nuts 34 each nest of tubes can be withdrawn immediately and repairs or cleaning effected with facility and expedition. As either combustion-chamber 15 may be operated independently of the other, the fire may be drawn in that one in which cleaning, adjustment, or repairs are required, while the other may be worked during the time such operations are being carried on. Thus the steam and water circulation may be continued through the entire system, excepting the nest, which is cut out for any required purpose.

In order that either combustion-chamber 25 may be used independently of the other in the use of forced draft, the foundation 1' is constructed to form a division-wall between the two ash-pits. To provide for readily cleaning off the tubes and baffles, hollow stay tubes 30 or openings, as 41', may be employed in convenient locations, through which steam may be blown.

It will be understood that sinuous or any other usual form of header adapted to this construction may be employed and that the mechanical details may be changed otherwise, as found expedient.

I claim—

1. In a boiler, a drum, a header having a 40 separable valve connection with a passage leading from said drum, a second header having a separable valved connection with a passage leading to said drum, whereby said headers may be cut off and separated from said 45 drum, means for keeping said passages closed aftersaid headers are removed and water-passages connecting said headers, substantially as specified.

2. In a boiler, a drum, a series of sectional 50 headers having connections with the passages leading from said drum, a valve for cutting off each header from communication with said passages, a second series of sectional headers having connections with the passages 55 leading to said drum, a valve for cutting off each of said second headers from communication with said second passages, and passages connecting said first and second headers, substantially as specified.

60 3. In a boiler, a drum, water-legs connected with said drum, a water-box connecting said water-legs, a header resting upon said water-box, a separable connection between said headers and said water-box, a valve for cutting off said header from said water-box, a second header connected with said first header,

a passage having a separable connection with said second header and leading to said drum, and a valve for cutting off said second header from said drum, substantially as specified.

4. In a boiler, a drum, water-legs connected with said drum, a water-box connecting said water-legs, headers resting loosely upon said water-box, water-passages connecting said headers and said water-box, a second set of headers having water-passages connected with said first set of headers, a support upon which said second headers rest loosely, and water-passages connecting said second headers and said drum, substantially as specified.

5. In a boiler, a drum, water-legs connected with said drum, a water-box connecting said water-legs, sectional headers resting loosely upon said water-box, water-passages connecting said headers with said water-box, and means for disconnecting said headers therefrom, valves for cutting off said headers from said water-box, a second set of sectional headers loosely supported and connected respectively with said first headers, water-passages connecting said second headers with said drum and means for disconnecting said headers therefrom, and valves for cutting off said second headers from said drum, substantially as specified.

6. In a boiler, a drum, water-legs connected at the respective ends and intermediate of said drum, a second set of water-legs and water-passages therefor connected respectively with said first water-legs, insulating material forming with said passages end walls and a division-wall, water-boxes connecting said first water-legs, sectional headers, valved connections between said headers and said water-boxes, a second set of sectional headers and water-passages between the same and said first headers, water-passages connecting said second headers with said drum, and valved connections between said second headers and said drum, substantially as specified.

7. In a boiler, a drum, water-legs connected therewith, a water-box connecting said water-legs, sectional headers loosely supported on said water-box, separable valved connections between said headers and said water-box, a second set of headers connected with said first headers, supports upon which said second headers loosely rest, apertures which permit access for adjustment, and separable valved passages connecting said second headers with said drum, substantially as specified.

8. In combination, a water-box, a header, a bend connecting said water-box and header, a valve for cutting off said water-box from said header, and means for disconnecting said header from said water-box, substantially as specified.

9. In combination, a water-box, a chair supported thereon, a header supported by said chair, a nipple connected with said water-box, a nipple connected with said header, a joint connecting said nipples, a valve for con-

trolling the passage from said water-box, and a hand-hole cap for access to the passage leading to said header, substantially as specified.

10. In combination, a water-tube, a header sleeved and clamped thereon, a port or ports in said tube communicating with said header, and a valve longitudinally movable within said tube to close the same, substantially as specified.

11. In combination, a water-tube, a header sleeved and clamped thereon, a port in said tube communicating with said header, a con-

ical flare in said tube, a conical valve longitudinally movable within said tube to close the same, a removable plug for the ends of 15 said tube through which said valve's stem is operated, substantially as specified.

In testimony whereof I have hereunto set my hand in the presence of the subscribing witnesses.

AXEL S. VOGT.
